S. GAGE

PASSENGER VEHICLE

Filed Dec. 27, 1920

Inventor
Samuel Gage,
Bakerell, Gymer, Ponmelle,
his Atty.

UNITED STATES PATENT OFFICE.

SAMUEL GAGE, OF HOLLOWAY, LONDON, ENGLAND, ASSIGNOR TO THE LONDON GENERAL OMNIBUS COMPANY, LIMITED, OF BROADWAY, WESTMINSTER, ENGLAND.

PASSENGER VEHICLE.

Application filed December 27, 1920. Serial No. 433,095.

To all whom it may concern:

Be it known that I, SAMUEL GAGE, subject of the King of England, residing at Holloway, London, England, have invented certain new and useful Improvements in Passenger Vehicles, of which the following is a specification.

This invention is for improvements in or relating to passenger vehicles of the type in which passengers are carried inside, and on the roof of, the body, and in which a platform outside one end of the body and staircase extending therefrom, also outside the body, to the roof thereof are provided. Many constructions of omnibus are included in this type of vehicle, and the invention is particularly applicable to omnibuses. The invention has for one of its objects to provide a construction of vehicle which shall be both strong and light, the requisite support being given to the aforesaid platform and staircase without imposing severe stresses upon the body of the vehicle and consequently without necessitating a heavy construction of the latter.

In building omnibuses it is convenient to construct the staircase and platform as separate units or entities from the body of the omnibus, if when this is done the chassis of the vehicle only extends to the rear of the body, as has been the case in some previous constructions, and the platform and staircase are left to be entirely supported from the end of the body, the body has to be stiffened and strengthened with rather heavy metal plates besides having to be generally of heavier construction than would otherwise be necessary. In the arrangement according to the present invention, however, the chassis is in the known manner extended beyond the rear of the body and receives the platform and staircase, supporting their weight. The platform and staircase, of course, are anchored to the rear of the body but the latter does not support their weight and consequently, being relieved of these stresses, can be made lighter in construction than heretofore.

For a more complete understanding of the invention there will now be described, by way of example only and with reference to the accompanying drawings, one constructional form of omnibus according to the invention. It is to be understood, however,

that the invention is not limited to the precise constructional details set forth.

In these drawings:

Figure 1 is a side elevation of the rear end of an omnibus;

Figure 2 is an underplan of the parts shown in Figure 1;

Figure 3 is a detail view on a scale larger than that of Figures 1 and 2, and

Figure 4 is a section on the line 4—4 of Figure 3, but on a scale larger than that of this figure.

Like reference numerals indicate like parts throughout the drawings.

The vehicle illustrated comprises an enclosed body 10 and a roof or upper deck 11 which are both provided with seats for the reception of passengers. At the rear of the vehicle there is a platform 12, preferably in the form of a slatted structure, to receive passengers entering or leaving the body 10 of the vehicle or passing up or down the staircase 13 leading to the upper deck 11. This slatted platform 12 is shown as being provided with two bars 14 and 15 on its under side which are secured by bolts, coach screws, or other suitable means 16 to suitable transverse members 17 and 18 on the under part of the body of the vehicle. This connection supports the platform and staircase to a certain extent, and also assists to retain them in correct position, but the main support for the weight of the platform and staircase is constituted by the chassis longitudinals 19 and 20 which, as will be clearly seen from an inspection of Figure 2, extend beyond the rear of the body and underneath the platform 12. The latter is secured to the longitudinals 19 and 20 by bolts or screws 21 and metal straps 22. The longitudinals 19 and 20 may be secured either, as illustrated, directly to the platform 12, or they may reach under the bars 14 and 15 and be secured through them to the platform. Between the longitudinals 19 and 20 and the platform there may be provided a suitable packing of felt, rubber or other suitable material to lessen vibration.

A metal plate 23 curved to form a fillet may be provided between the upper surface of the platform 12 and the floor of the body 10, and the bars 14 and 15 may be strengthened by angle plates 24 if desired. The staircase 13 is shown as resting at its bottom end

on the platform and attached at its upper end to the roof structure of the omnibus, and the platform carries a vertical pillar 25 dividing it into two portions, one to serve 5 the staircase and the other to serve the interior of the omnibus. A step 26 intermediate of the platform 12 and the ground is shown in chain lines in Figures 1 and 2, together with its supports 27 whereby it is secured 10 to the platform. The bars 14 and 15 may have lightening recesses 28 and the angle plates 24 lightening holes 29.

From the foregoing it will be appreciated 15 that there is provided according to the present invention a construction of vehicle which is strong and light and in which the platform and staircase are supported in a thoroughly efficient manner.

What I claim as my invention and desire 20 to secure by Letters Patent is:—

1. In a double-deck motor-driven omnibus, the combination of an enclosed body constituting the lower-deck and having a door-opening in the rear end thereof, an upper-deck terminating at its rear end substantially 25 with the rear end of said body, a seatless platform distinct from and situated outside the rear end of said body and affording the means of ingress to and of egress from the 30 body through said door-opening, a staircase having its lower end attached to said platform and extending therefrom outside the body and the said upper-deck, a chassis having main longitudinals which support the 35 bottom of said body and have rear portions

that extend beyond the rear end of the body on which rear portions the platform is seated, whereby its weight and the weight of the staircase is borne by the same, and platform-bars secured at their one end directly to the 40 underside of the bottom of said body, which bars extend under and are attached to the platform for securing the latter and the bottom of the staircase in correct position in relation to the body, substantially as described. 45

2. In a double-deck omnibus, a pair of longitudinally extending spaced chassis members, an enclosed body carried by said members and having a door-opening in the rear end thereof, said body terminating short of the rear end of said members, a seatless platform to the rear of said body and supported on said members and affording the means of ingress to and of egress 50 from the body through said door-opening, supplemental platform members secured at their front ends to the underside of said body and extending under and serving as additional supports for said platform, said body having a passenger-carrying roof terminating at its rear end substantially with the rear end of said body, and a staircase to the rear of said body and supported at its lower end on said platform whereby the weight thereof is carried by said platform, substantially as described. 55 60

In testimony whereof I affix my signature

SAMUEL GAGE.
